BAND PASS AMPLIFIER

Bernardus Dominicus Hubertus Tellegen, Eindhoven, Netherlands, assignor to Radio Corporation of America, a corporation of Delaware

Application July 7, 1930, Serial No. 465,972, and
in the Netherlands August 3, 1929

5 Claims. (Cl. 178—44)

The present invention relates to band pass filters which are particularly adapted to be used in wireless receiving sets.

It is known that when transmitting telephony a definite band width must be strongly received, while the frequencies lying immediately outside of this band should be suppressed as much as possible. A rectangular resonance curve is often considered to be ideal. Thereby, a band, whose width corresponds to the range of speech or music frequencies, is received with a constant intensity, while the higher and lower frequencies are not received at all.

Such a rectangular resonance curve can, however, not be obtained with the aid of available means. In fact, all of the curves indicating the current intensity, or the voltage, occurring in an impedance in dependence of the frequency have a more or less smooth shape, and it has been almost impossible to design a combination such that the frequencies below, or above, a certain limit are completely excluded. Although by using coupled circuits this rectangular resonance curve may be approximately more or less closely, it appears that the frequencies lying immediately outside of the range which is desired to be received, are still allowed to pass at an intensity which is too high to assure a sufficient elimination of these undesired frequencies.

This invention has for its main object the provision of a new method by means of which the shape of the resonance curve which has been considered hereinbefore as being ideal, is more closely approximated than it has been possible by using the systems hitherto known. The principle of the invention involves the combination of impedances so chosen, that immediately before, and immediately after, the range which must be strongly received one or more minima occur in the total resonance curve. Although in these circumstances the resonance curve will slightly rise over a certain distance as well in the direction of the higher side as in the direction of the lower side, it has appeared that the advantages obtained by applying the aforementioned principle, are retained thereby.

The novel features which I believe to be characteristic of my invention are set forth in particularity in the appended claims, the invention itself, however, as to both its organization and method of operation will best be understood by reference to the following description taken in connection with the drawing in which I have indicated diagrammatically several circuit organ-

izations whereby my invention may be carried into effect.

The invention will be more clearly understood by reference to the accompanying drawing, representing in Figs. 1 to 5 inclusive various embodiments of band pass filters according to the invention.

In Fig. 1 the band pass filter consists of a stopping circuit L_1, C_1 , connected in series to an inductance L_3 . This inductance L_3 is magnetically coupled with an inductance L_4 whose terminals are connected across a series connected combination consisting of an inductance L_2 and a capacity C_2 . Let it be assumed that a voltage be applied to the points a and b , and that the voltage is collected at the points c and d , then it can be shown that the proportion between the output voltage and the input voltage becomes equal to zero at the frequencies:

75

$$\omega_1 = \sqrt{\frac{1}{L_1 C_1}}$$

and

$$\omega_2 = \sqrt{\frac{1}{L_2 C_2}}$$

80

This proportion is, of course, only zero if the damping caused by ohmic resistances is not taken into consideration. However, it will be obvious, that even in presence of ohmic resistances, minima of the resonance curve may occur at the frequencies ω_1 and ω_2 . When the damping increases, the minima may become less sharp, or even completely disappear, without the effect obtained being entirely lost.

The frequencies ω_1 and ω_2 are on either side of the frequency band to be transmitted. If ω_1 is the lowest frequency the resonance curve will, first, rise steeply immediately subsequent to ω_1 , and, then, show a plane shape for a certain distance. Thereupon, it will steeply descend immediately preceding ω_2 , and slowly rise subsequent to ω_2 . At any rate, the permeability in this case will remain small with respect to that which is encountered by the desired frequency. By a suitable choice of impedances the peak of the resonance curve will substantially extend parallel with respect to the axis of the frequency.

A still better result may be obtained by applying the diagram shown in Fig. 2, comprising a circuit L_1, C_1, C_3 which, by means of the capacity C_4 , is capacitively coupled with the circuit L_5, C_5 , the latter being in turn magnetically coupled with the circuit L_6, C_2, L_2 . When a current is supplied at the points a and b , and the voltage is collected at the points c and d , the ratio between

105

110

the output voltage and the input current will be zero with the frequency:

$$\omega_1 = \sqrt{\frac{1}{L_1 C_1}}$$

5 and

$$\omega_2 = \sqrt{\frac{1}{L_2 C_2}}$$

For these frequencies minima will occur again, 10 while between these frequencies the resonance curve has the same shape as that belonging to the system shown in Fig. 1. The supply of a current between the points *a* and *b* may preferably be effected by inserting the filter in the anode circuit 15 of a triode, or of a tetrode, having a high internal resistance in the manner as indicated in Fig. 2. The connection with the next triode may be established by connecting the points *c* and *d* respectively to the grid and the cathode of said next 20 triode.

In Fig. 3, a system is shown which is identical to the system illustrated in Fig. 2. In this case the capacitive coupling which is effected by the capacity of C_4 , indicated in Fig. 2, is replaced by 25 a coupling established by means of a thermionic device 2. The operation of the circuit remains, however, the same; only the dependency between both parts of the filter included in the system shown in Fig. 3 is a little less strong as it is the case in the system represented in Fig. 2. In fact, 30 the value of the capacity C_4 in Fig. 4, also, determines the position of the resonance frequencies while the triode 2 shown in Fig. 3 only very slightly acts upon the resonance frequencies, so that 35 the properties of the system shown in Fig. 3 may easily be derived from the properties of both parts individually which are coupled together by means of the triode. With the filters shown in Figs. 2 and 3 the feeding of the plates may be effected by 40 inserting choke coils and a source of current between the points *a* and *b*.

Figs. 4 and 5 present some further filters in 45 which the invention is embodied and whereby no separate choke coils are needed for feeding the plates. Also with these filters there occur minima in the frequencies which are determined by L_1 , C_1 and L_2 , C_2 .

By properly proportioning the variable components of the systems described hereinbefore the 50 whole filter circuit may be rendered tunable so that the width of the frequency band which is allowed to pass remains substantially constant. In some cases the filter circuit need not be tunable, especially in case it is applied in super- 55 heterodyne receiving sets. In the latter case the filter may be made so as to constitute an intermediate frequency filter. Furthermore, a permanent filter may be applied when transmitting high frequency telephony along lines; since 60 thereby only a number of fixed wave lengths are used each receiver may be given his own filter.

While I have indicated and described several 65 systems for carrying my invention into effect, it will be apparent to one skilled in the art that my invention is by no means limited to the particular organizations shown and described, but that many modifications in the circuit arrangements, as well as in the apparatus employed, may be made without departing from the scope of my invention as set forth in the appended claims.

What I claim is:

1. In an electric transmission system, a source 70 of high frequency energy, means for utilizing the energy, means for coupling the source to said utilizing means, an oscillatory circuit connected

between said source and said coupling, an oscillatory circuit connected in shunt with said coupling and disposed between the latter and the utilizing means, said first oscillatory circuit being resonant to one limiting frequency of a desired band of frequencies, and the second oscillatory circuit being resonant to the other limiting frequency of said band whereby the resonance curve of the system rises steeply at each 80 limiting frequency, has a plane shape for a certain distance between the steep points and rises slowly outside the limiting frequencies.

2. In an electric transmission system, a source 85 of high frequency energy, means for utilizing the energy, means for coupling the source to said utilizing means, an oscillatory circuit connected between said source and said coupling, an oscillatory circuit connected in shunt with said coupling and disposed between the latter and the utilizing means, said first oscillatory circuit being resonant to one limiting frequency of a desired band of frequencies, and the second oscillatory circuit being resonant to the other limiting frequency of said band whereby the resonance curve of the system rises steeply at each 90 limiting frequency, has a plane shape for a certain distance between the steep points and rises slowly outside the limiting frequencies, said first limiting frequency being the lowest frequency of the said band, and the second limiting frequency being the highest frequency of the band.

3. In an electric transmission system, a source 95 of high frequency energy, means for utilizing the energy, means for coupling the source to said utilizing means, an oscillatory circuit connected in series between said source and one side of said coupling, an oscillatory circuit connected in shunt with said coupling and disposed between the latter and the utilizing means, said first oscillatory circuit being resonant to one limiting frequency of a desired band of frequencies, and the second oscillatory circuit being resonant to the other limiting frequency of said band whereby the resonance curve of the system rises steeply at each 100 limiting frequency, has a plane shape for a certain distance between the steep points and rises slowly outside the limiting frequencies, said first limiting frequency being the lowest frequency of the said band, and the second limiting frequency being the highest frequency of the band.

4. In an electric transmission system, a source 105 of high frequency energy, means for utilizing the energy, means for coupling the source to said utilizing means, an oscillatory circuit connected in series between said source and one side of said coupling, an oscillatory circuit connected in shunt with said coupling and disposed between the latter and the utilizing means, said first oscillatory circuit being resonant to one limiting frequency of a desired band of frequencies, and the second oscillatory circuit being resonant to the other limiting frequency of said band whereby the resonance curve of the system rises steeply at each 110 limiting frequency, has a plane shape for a certain distance between the steep points and rises slowly outside the limiting frequencies.

4. In an electric transmission system, a source 115 of high frequency energy, means for utilizing the energy, means for coupling the source to said utilizing means, an oscillatory circuit connected in series between said source and one side of said coupling, an oscillatory circuit connected in shunt with said coupling and disposed between the latter and the utilizing means, said first oscillatory circuit being resonant to one limiting frequency of a desired band of frequencies, and the second oscillatory circuit being resonant to the other limiting frequency of said band whereby the resonance curve of the system rises steeply at each 120 limiting frequency, has a plane shape for a certain distance between the steep points and rises slowly outside the limiting frequencies.

5. In an electric transmission system, a source 125 of high frequency energy, means for utilizing the energy, means for coupling the source to said utilizing means, an oscillatory circuit connected in series between said source and one side of said coupling, an oscillatory circuit connected in shunt with said coupling and disposed between the latter and the utilizing means, said first oscillatory circuit being resonant to one limiting frequency of a desired band of frequencies, and the second oscillatory circuit being resonant to the other limiting frequency of said band whereby the resonance curve of the system rises steeply at each 130 limiting frequency, has a plane shape for a certain distance between the steep points and rises slowly outside the limiting frequencies.

5. In an electric transmission system, a source 135 of high frequency energy, means for utilizing the energy, means for coupling the source to said utilizing means, an oscillatory circuit connected in series between said source and one side of said coupling, an oscillatory circuit connected in shunt with said coupling and disposed between the latter and the utilizing means, said first oscillatory circuit being resonant to one limiting frequency of a desired band of frequencies, and the second oscillatory circuit being resonant to the other limiting frequency of said band whereby the resonance curve of the system rises steeply at each 140 limiting frequency, has a plane shape for a certain distance between the steep points and rises slowly outside the limiting frequencies.

5. In an electric transmission system, a source 145 of high frequency energy, means for utilizing the energy, means for coupling the source to said utilizing means, an oscillatory circuit connected in series between said source and one side of said coupling, an oscillatory circuit connected in shunt with said coupling and disposed between the latter and the utilizing means, said first oscillatory circuit being resonant to one limiting frequency of a desired band of frequencies, and the second oscillatory circuit being resonant to the other limiting frequency of said band whereby the resonance curve of the system rises steeply at each 150 limiting frequency, has a plane shape for a certain distance between the steep points and rises slowly outside the limiting frequencies.

ing resonant to one limiting frequency of a desired band of frequencies, the second oscillatory circuit being resonant to the other limiting frequency of said band whereby the resonance 5 curve of the system rises steeply at each limiting frequency, has a plane shape for a certain distance between the steep points and rises slowly outside the limiting frequencies, said

source comprising an electron discharge tube having a high internal resistance, said coupling means consisting of a transformer and additional capacitive means coupling said first oscillatory circuit and said transformer.
